UNITED STATES PATENT OFFICE.

GARDNER E. SCHWARTZ, OF WALDOBORO, MAINE.

HAT-PIN GUARD.

1,215,204.

Specification of Letters Patent. Patented Feb. 6, 1917.

Application filed May 8, 1913. Serial No. 766,389.

To all whom it may concern:

Be it known that I, GARDNER E. SCHWARTZ, a citizen of the United States, residing at Waldoboro, in the county of Lincoln and State of Maine, have invented certain new and useful Improvements in Hat-Pin Guards; and I do hereby declare the following to be a full, clear, and exact description of the invention, such as will enable others skilled in the art to which it appertains to make and use the same.

This invention relates to new and useful improvements in hat pin guards, and has for its object to provide a device of the above character which will firmly clamp the point of a hat pin and will still be ornamental when in position.

Another object of my invention is to provide a device which may be attached to a hat and which will remain attached thereto, thus preventing loss or displacement of the same.

A still further object of my invention is to provide a hat pin point protector having a bent shank in which the point of a pin is adapted to be inserted and firmly held therein by frictional engagement with the sides thereof.

With the above and other objects in view, I will now proceed to describe my invention in the following specification and accompanying drawings, in which,

Figure 1 is a side view in elevation of a hat showing the same with my improved guard applied thereto;

Fig. 2 is a fragmental view of a hat showing my device in place;

Fig. 3 is a longitudinal sectional view of my improved hat pin protector as it would appear with a hat pin in place; and

Fig. 4 is a transverse sectional view of Fig. 3.

Referring to the drawings by characters of reference, 5 indicates generally a hat, comprising the usual crown 6 and the brim 7. The usual hat band 8 surrounds the crown adjacent the brim, and is secured thereto in the usual manner.

My improved hat pin guard is secured to the hat by means of the attaching members 9, which are adapted to be stitched to the hat band, as clearly illustrated in Fig. 1,

and are connected by means of the chain 10 which passes through the apertures 11 in the attaching member 9.

A tubular shank 12 is provided and is adapted to receive the end of the pin 13, as clearly illustrated in Fig. 3. One end of the tubular member 12 is preferably closed by the wall 14, which is adapted to limit the inward movement of the pin and form an abutment against which the point of the pin is adapted to contact when the device is in place. A flared portion 15 is provided at the opposite end of the tubular member 12 and is offset, as clearly illustrated in the drawings. This flared portion 15 is adapted to guide the point of the pin when the same is being put in place. A suitable loop 16 is formed integral with the flared portion at the point where the flared portion joins the tubular portion, and is adapted to slide on the chain 10 so that, regardless of where the hat pin projects through the hat, providing it be intermediate the attaching members 9, it will be possible to slide the guard along the chain and slip it over the end of the pin, thereby holding the device from accidental displacement.

In use the attaching members 9 are secured in place, as described, and when the point of the pin projects through the crown of the hat, the protector may be slid along the chain until it reaches the desired point. It will then be possible to insert the point of a pin into the flared opening, which will guide the same until it reaches the reduced portion. Upon further pressure of the pin inwardly, it will be obvious that the same will bind between the offset portion and the free ends, as clearly illustrated in Fig. 3, thereby holding the device from accidental movement.

While in the foregoing I have shown and described the preferred embodiment of my invention, I wish it to be understood that I may change the specific arrangements of parts without in any way departing from the spirit and scope of my invention.

Having thus fully described my invention, what I claim is:

A hat pin guard comprising a funnel shaped member and a tubular member, said

tubular member extending angularly from the apex of the funnel shaped member and in such a position that a portion thereof extends in an upwardly inclined plane with relation to the bottom wall of the tubular member, the upwardly inclined portion and the top wall of the tubular member being adapted to engage and grip a hat pin and a

loop formed on the members at the point where they join to form attaching means. 10

In testimony whereof I affix my signature in presence of two witnesses.

GARDNER E. SCHWARTZ.

Witnesses:

BESSIE S. KUHN,
MAYNARD H. KUHN.
